Specification for Design.

Patented Oct. 11, 1921.

Application filed September 13, 1920. Serial No. 410,019. Term of patent 7 years.

To all whom it may concern:

Be it known that I, HERBERT A. KAITTING, a subject of the King of Great Britain, residing at the city of Galt, in the county of Waterloo, in the Province of Ontario, Canada, have invented a new, original, and ornamental Design for Blind-Holding Windshield-Clips, of which the following is a specification, reference being had to the ac-

companying drawing, forming part thereof, in which—

Figure 1 is a front elevation of the clip;
Fig. 2 is a side view; and

Fig. 3 is a plan view.

I claim:

The ornamental design for a blind-holding windshield clip, as shown.

HERBERT A. KAITTING.
